UNITED STATES PATENT OFFICE.

FRANK A. SHOEMAKER, OF BUFFALO, NEW YORK, ASSIGNOR TO STURDY SMOKELESS FURNACE COMPANY, OF BUFFALO, NEW YORK, A CORPORATION OF NEW YORK.

SMOKELESS BOILER-FURNACE.

1,097,735.

Specification of Letters Patent.

Patented May 26, 1914.

Application filed July 5, 1912. Serial No. 707,722.

To all whom it may concern:

Be it known that I, FRANK A. SHOEMAKER, a citizen of the United States, residing at Buffalo, in the county of Erie and 5 State of New York, have invented new and useful Improvements in Smokeless Boiler-Furnaces, of which the following is a specification.

My invention relates to boiler furnaces 10 and more particularly to a smokeless boiler furnace; it having for its objects the provision of a furnace whereby the products of combustion may be practically entirely consumed and the fuel economically used, also 15 the provision of means for conveniently converting the furnace from a natural draft to a forced draft furnace; to provide means for conveniently and quickly disposing of clinkers within the firing chambers; to so 20 arrange the same that the water tubes thereof may be easily blown off to clear the same of sediment; and to otherwise improve on boiler furnaces of this type.

The invention consists in the arrangement 25 and construction of parts to be hereinafter described and particularly pointed out in the subjoined claims.

In this improved boiler furnace any suitable boiler may be used in connection with 30 the other portion of the furnace, and it has a combustion chamber in such relation to the boiler that the products of combustion act most efficiently against the same in its course to the smokestack. Firing chambers 35 are provided at opposite sides of the combustion chamber with water tubes arranged in series and serving as divisional walls between the combustion chamber and the firing chambers, said water tubes being arranged upright and having manifolds at opposite ends which are connected with the boiler to provide means for a perfect circulation of the water through these walls. Beneath the combustion chamber a forced air 40 draft compartment is provided which is in communication with the firing chambers through the ash pits and the fire grates of the firing chambers, the outer sides of the latter being provided with fixed inclined 45 fire grates and oscillating fire grates formed of bars capable of being moved toward and from the main grate bars so as to enlarge or diminish the spaces between the two, whereby clinkers may be removed from the 50 firing chambers when the spaces between 55

said oscillating grates and the main grates are enlarged, and means for actuating said oscillating grates. The lower ends of the walls separating the firing chambers from the combustion chamber are provided with 60 means for blowing off said walls and the boiler so as to clear them of sediment and other matter.

In the drawings,—Figure 1 is a longitudinal section of my improved boiler furnace, 65 the boiler being shown in elevation. Fig. 2 is a vertical longitudinal section through one of the divisional walls separating the combustion chamber from the firing chambers. Fig. 3 is a detached perspective view 70 of one end of one of the oscillating fire grates. Fig. 4 is a transverse section on an enlarged scale, taken on line 4—4, Fig. 1. Fig. 5 is a section on a reduced scale, taken on line 5—5, Fig. 4. Fig. 6 is a broken longitudinal section taken on line 5—5, Fig. 4. 75

Referring now to the drawings in detail like numerals of reference refer to like parts in the several figures.

The furnace has the usual brick inclosure 80 comprising a front wall 7, the side walls 8, 9, the rear wall 10, and top wall 11. Within said inclosure is applied any suitable boiler 12, that shown being an ordinary flue 85 boiler supported in any suitable manner. At the rear of the boiler is a plate 13 which extends from side wall to side wall so as to direct the products of combustion through the flues of the boiler and into the smokestack 14. Arranged centrally underneath 90 the front portion of the boiler is a combustion chamber 15 which opens at its rear end into the compartment or passage 16 which extends underneath, and around the sides of the boiler 12 and upwardly in rear of the 95 latter. The boiler 12 serves as the top wall of the combustion chamber so that the flame and heat come in direct contact with the boiler throughout its length.

Arranged at opposite sides of the combustion chamber are firing chambers 17 which are separated from the combustion chamber by articulated divisional walls 18, comprising preferably upright water tubes 19 having horizontally disposed circular upper 100 and lower ends or heads 20 which are brought together and connected in any suitable manner to create manifolds at the upper and lower ends of the divisional wall thus formed. The lower manifold of each 110

divisional wall has connection with the boiler 12 by means of a pipe 21 and the upper manifold of each divisional wall has connection with the boiler by a return pipe 22. The divisional walls are therefore formed of connected sections and in order that the sections may be exact counterparts, I provide at opposite ends of each manifold chambers 23 which are of substantially the same cross-sectional formation as the manifold and serve to close the ends of the latter. One of the chambers of each lower manifold has the pipe 21 threaded thereinto, as at 24, Fig. 2, and the other chamber has a blow-off pipe 25 threaded thereinto, said blow-off pipe being adapted to be led to a sewer, directly or indirectly, or to any other suitable place, as shown in Fig. 1. Said pipe 25 is provided with a suitable valve 26 which is closed, except when cleaning out the boiler 12 and divisional walls 18. One of the chambers 23 of each upper manifold has its coöperating return pipe 22 threaded thereinto and its end wall provided with a threaded opening closed by a plug 27 which may be removed to obtain access to the interior of the manifold, this being desirable in the particular construction disclosed owing to the fact that within one of the chambers 23 of each manifold perforated lugs 28 are interiorly provided through which is passed one of the ends of tie rods 29, said rods being inserted through the opposite chamber 23 and having nuts 30 applied to opposite ends, which upon being tightened upon said rods draw the sections of the divisional walls securely together, suitable packing 31 being provided between the heads 20 to prevent leakage of water. The tie rods of the lower manifold are accessible through the opening 32 into which the blow-off pipe 25 is threaded, so that by removing said blow-off pipe and the plug 27 of the upper manifold, the tie-rods may be reached to permit separation of the several sections constituting the divisional wall, for making repairs or otherwise.

The firing chambers 17 are closed at the rear by walls 33 and at the top by walls 34 extending from the sides 8, 9, to the boiler and also by vertical walls 35 extending downward from the boiler to the upper manifold. The tubes constituting the divisional walls 18 between the combustion chamber and the firing chambers are separated from each other at points between the manifolds by intervening spaces 36, except along the upper ends of the tubes at which point they are provided with webs or fins 37 which extend downwardly from the upper manifolds a suitable distance with the webs or fins of each tube lying in contact with those of adjoining tubes. The firing chambers are therefore in communication with the combustion chamber only at points

between the lower ends of said webs or fins and the lower manifolds, for a purpose to be hereinafter described.

Beneath the combustion chamber is a forced draft chamber 38 which is separated from said combustion chamber by the wall 39, and on opposite sides of said forced draft chamber are ash pits 40 separated from said forced draft chamber by walls 41 which serve as supports for the wall 39, the divisional walls 18 and the inner ends of horizontal or main fire grates 42 arranged between the firing chambers and the ash pits, the outer ends of said grates being supported in the side walls, 8, 9, as at 43. The forced draft chamber 38 is in communication with the ash pits 40 by means of passages 44 arranged in the walls 41, and by means of a fan or other apparatus the forced draft may be introduced into the firing chambers from the forced draft chamber 38, but it is apparent that this boiler furnace is also adapted for use in the ordinary way without introducing the forced draft feature into it.

The grate bars of the horizontal or main fire grates 42 extend only through a portion of the width of the grates, so as to leave a comparatively large space or opening 45 between said bars and the side walls 8, 9, as best shown in Fig. 4, and in connection with said grates I employ inclined grates 46, 47, which are arranged to project inwardly and downwardly, said inclined grates being in planes directly above the spaces or openings 45 provided between the grate bars of the main fire grates 42 and the side walls. The inclined grates are preferably arranged in pairs at each side of the furnace, one grate, designated 46, of each pair being fixed and the other, designated 47, being arranged for movement toward and from the grate-bars of the main grates 42. The fixed inclined grates 46 are arranged above the movable inclined grates 47 and are supported upon brackets 48 secured to the side walls 8, 9, the bars of said fixed inclined grates being held against upward movement by abutments 49 built in said walls and being removable only by loosening the brackets 48. The grate-bars of said fixed inclined grates rest directly upon a longitudinally-disposed bar 50 carried by said brackets. Within the brackets 48, which are arranged in pairs at each side of the furnace, are journaled shafts 51 to each of which is secured a series or set of grate-bars or teeth 52, said grate-bars or teeth and said shafts constituting the movable grates 47. To the end grate-bars or teeth 52 of each series or set are connected one of the ends of toggles 53, the other end of each toggle being secured to a square actuating rod 54, which is journaled in plates 55 secured to the brackets 48 and having toggle 130

6 supports 56 which rest upon the main grates 42, the forward ends of said square rods extend outwardly through the front wall and are rendered accessible by opening the fire and clinker doors 57 of the firing chambers.

10 The fixed inclined grates 46 are so arranged with reference to the movable or oscillating inclined grates 47 that the fuel moving downward in the firing chambers is prevented from packing, since it is necessary that the fuel passes over the lower ends 15 of the grate-bars of said fixed grates, which ends are at the restricted portions of the firing chambers, and then passes into the enlarged lower end.

20 As is common in boiler furnaces, the ash pits have doors 58 and in order to feed fuel into the firing chambers, doors 59 are provided in the front wall of the furnace in line with the upper portion of said chambers. A door 60 may be provided in the front wall for access to the combustion chamber and, if desired, a door 61 may be 25 provided for access to the forced draft chamber. The side walls are provided with depressions 62 in their inner faces directly outside of the fixed inclined grates 46 so that the necessary space is provided outside 30 of said grates to permit the passage of air through the latter.

35 In the operation of the furnace, the fuel is fed into the firing chambers 17 through the doors 59, the fuel being preferably arranged to a depth to entirely cover the three grates of each firing chamber, the divisional walls 18 between the combustion chamber 15 and said firing chambers preventing the fuel passing into the combustion 40 chamber and as said divisional walls are formed of tubes containing water they cannot readily burn out. The air is applied to the fuel through the openings closed by the door 59 and through the door openings of 45 the ash pits or when a forced draft is relied upon it may be furnished from the forced draft 38, from which it may pass into the ash pits through the passages 44 and thence upwardly through the fire grates. 50 The flame and gases escape from the fuel through the tubular divisional walls 18 and enter the combustion chamber, the meeting flames and gases entering the combustion chamber from opposite sides commingle 55 with the air in the combustion chamber, which air is admitted in any suitable manner and brought in intimate contact with the gases so as to become immediately ignited and cause complete combustion of the 60 unconsumed gases. The flame and heat passes rearwardly in contact with the boiler and around the sides thereof, thence around the rear end of the boiler and through the flues thereof and finally into the smokestack, all 65 smoke being consumed within the combus-

tion chamber so that no smoke escapes from the furnace. The air admitted into the ash pits passes upwardly through the grates 37, through the movable inclined grates 47, into the spaces between the side walls and the 70 fixed inclined grates 46 and through the latter. In this manner a free and bountiful supply is furnished and spread over a large region within the firing chamber; thus assuring a good fire. When, however, it is desired to check the fire the doors 58 of the ash pit may be closed, also the fuel doors 59 and the door 60 of the combustion chamber opened. In this manner the fires are banked and may be retained in such condition for 80 many hours.

85 In order to dispose of the clinkers it is simply necessary to apply a wrench or other suitable tool to the ends of the square actuating rods 54, which cause the toggles 53 to assume the position shown in dotted lines Fig. 4, thus causing the oscillating grate-bars or teeth 52 to swing from the position shown in full lines in said figure to that shown in dotted lines. In other words, 90 by the actuation of the toggles the movable or oscillating grates are caused to swing away from the main fire-grates 42 and provide a space between the two for the ready removal of clinkers from the firing chambers, access to the firing chambers being had for this purpose through the openings closed by the doors 57.

95 In order to blow off the boiler 12 and the tubular divisional walls 18 it is simply necessary to open the valve 26 in the blow-off pipe, whereupon the water in the boiler and said walls passes off under force of the steam and carries with it all sediment.

100 In the operation of the furnace the amount of labor required is reduced to the minimum and all parts of the interior are readily accessible. The construction shown and described assures perfect combustion and complete consumption of all smoke even 105 when supplying the furnace with fresh fuel, and by means of my improved arrangement for blowing-off the tubular divisional walls and boiler the highest heat efficiency 110 is obtained owing to the interior of both 115 being thereby easily kept in clean condition.

Having thus described my invention, what I claim is,—

120 1. A boiler furnace having a combustion chamber extending lengthwise, a tubular wall at one side of said combustion chamber, a firing chamber separated from said combustion chamber by said tubular wall and closed at its rear, top and outer side, a main grate serving as a bottom of said firing chamber, and an inclined grate supported from the outer side of said combustion chamber.

125 2. A boiler furnace having a combustion chamber

chamber, a forced draft chamber beneath said combustion chamber, a firing chamber at one side of said combustion chamber, and an articulated wall separating said firing chamber from said combustion chamber, said forced draft chamber and firing chamber being in communication.

3. A boiler furnace having a combustion chamber, a firing chamber, a wall separating said combustion from said firing chamber and having openings therein, a forced draft chamber beneath said combustion chamber and separated therefrom by a wall, an ash pit beneath said firing chamber and separated therefrom by a fire-grate, and passages connecting said forced draft chamber with said ash pit.

4. A boiler furnace having a combustion chamber extending lengthwise, a firing chamber at one side of said combustion chamber and also extending lengthwise, a divisional wall between said firing chamber and combustion chamber comprising upper and lower manifolds and tubes connecting said manifolds, and a blow-off pipe secured to one of said manifolds and having a valve therein.

5. A boiler furnace having a combustion chamber, a firing chamber at one side of said combustion chamber separated therefrom by an articulated wall, a fire-grate at the lower end of said firing chamber, and two fire-grates at the side of said firing chamber, one of said two fire-grates overhanging the other.

6. A boiler furnace having a combustion chamber, a firing chamber at one side of said combustion chamber closed at its rear end and at the top and separated from said combustion chamber by a wall having passages therein, a fire-grate at the lower end of said firing chamber having its grate-bars separated from the side wall of said firing chamber by a comparatively large space, an ash pit beneath said fire-grate and an inclined grate at the side of the firing chamber closing said comparatively large space from the fuel within said firing chamber.

7. A boiler furnace having a combustion chamber, two tubular walls at opposite sides of said combustion chamber extending lengthwise, firing chambers outside of said walls closed at the top and at their rear ends, ash pits beneath said firing chambers, fire-grates separating said ash-pits from said firing chambers and having grate-bars along their inner portions only to provide comparatively large openings at their outer portions, an inclined grate arranged above each of said large openings and adapted to be moved toward and from the grate-bars of the first-mentioned grates to permit the discharge of clinkers from the firing chambers.

8. A boiler furnace having a smokestack, a combustion chamber in communication

with said smokestack, firing chambers at opposite sides of said combustion chambers in communication with said smokestack through said combustion chamber only, an ash pit beneath each firing chamber, a fire-grate separating said ash pits from said firing chambers and comprising three sections, one of which is arranged horizontally and the others being inclined with respect to the outer side walls of the firing chambers, one of said inclined fire-grates being movable and the other rigid and overhanging the movable fire-grate.

9. A boiler furnace having a combustion chamber, a smokestack with which said combustion chamber is in communication, a series of water tubes arranged lengthwise at opposite sides of said combustion chamber and separated by intervening spaces, firing chambers outside of said water tubes and in communication with said smokestack through said combustion chamber only, an ash pit beneath each firing chamber, horizontally-disposed grates between each ash pit and the firing chamber directly above, said grates having grate-bars at their inner portions only, a bracket secured to the outer side wall of each firing chamber, fixed inclined fire-grates carried by said brackets, and an oscillating fire-grate beneath each fixed inclined fire-grate having its grate-bars inclined and normally extending from the grate-bars of the horizontally-disposed grates upwardly and outwardly, said fixed inclined fire-grates overhanging said oscillating fire-grates.

10. In a boiler furnace, a firing chamber having a horizontal fire-grate at its lower end provided with grate-bars extending from a point about midway between the outer side wall of the firing chamber to the inner wall thereof so as to provide a comparatively large opening in said grate between its grate-bars and said outer wall, an oscillating grate arranged above said openings and comprising a shaft suitably journaled, grate-bars inclined inwardly and downwardly from said shaft, a rod arranged parallel with said shaft, and a toggle connecting the oscillating grate with said rod whereby said oscillating grate is caused to swing toward and from the grate-bars of said horizontal grate.

11. In a boiler furnace, a firing chamber having a horizontal grate at its lower end with its grate-bars separated from the outer wall of said firing chamber by a comparatively large space, two inclined grate-bars ranging from the grate-bars of said horizontal fire-grate upward to said outer side wall, one of said grate-bars being fixed and the other being movable toward and from the grate-bars of said horizontal fire-grate, said fixed inclined fire-grate overhanging the movable fire-grate.

12. A boiler furnace having a combustion chamber, a firing chamber outside of said combustion chamber separated by a wall provided with passages, the outer wall 5 of said chamber having a depression arranged lengthwise along its inner face, a fire-grate arranged horizontally at the lower end of said firing chamber and having its grate-bars separated from said outer 10 wall by a comparatively large space, and an inclined fire-grate arranged lengthwise along said outer wall and extending therefrom toward the horizontal fire-grate to overlie the space in the latter and the depression in said outer side wall.

13. A boiler furnace having a combustion chamber, a firing chamber spaced at one side of said chamber and separated therefrom by a wall having passages connecting 20 both chambers, an ash pit beneath said firing chamber, a fire-grate between said ash

pit and said firing chamber and having a comparatively large opening between its grate-bars and the outer side wall of said firing chamber, brackets secured to said outer side wall, a longitudinally-disposed bar carried by said brackets, inclined grate-bars carried by said longitudinally-disposed bar, an oscillating grate beneath said inclined grate-bars and having inclined grate-bars extending upward and outward from the grate-bars of said first-mentioned fire-grate, and means for actuating said oscillating grate.

In testimony whereof, I have affixed my 35 signature in the presence of two subscribing witnesses.

FRANK A. SHOEMAKER.
